Ohio, assignors to The Goodyear Tire & Rubber Com-
pany, Akron, Ohio, a corporation of Ohio

Filed July 22, 1968, Ser. No. 12,852

Term of patent 14 years

Int. Cl. D12—14

U.S. Cl. D90—20

FIG. 1

FIG. 2

FIG. 3

FIGURE 1 is a perspective view of a tire showing our new design, it being understood that the full line portion of the design is repeated throughout the circumference of the tire, the opposite side being substantially the same as that shown.

FIGURE 2 is an enlarged fragmentary plan view of the tread portion of the tire shown in FIGURE 1; and

FIGURE 3 is a sectional view taken substantially on the plane indicated by line 3-3 of FIGURE 2.

The dominant features of the design reside in the portions shown in full lines in the drawings.

We claim:

The ornamental design for a tire, substantially as shown and described.
